UNITED STATES PATENT OFFICE

2,031,135

LATHE

Charles W. Smith, Grand Rapids, Mich.

Application February 26, 1934, Serial No. 712,943

6 Claims. (Cl. 142—42)

The present invention relates to lathes; and its object is, generally, to provide a lathe improved in various respects hereinafter appearing; and more particularly, to provide in a lathe a lathe stock having a member freely rotatable about the axis of the lathe's turning operation with a coaxial bore through which the work is axially fed but is held against transaxial movement; and further, to provide in connection with such a stock a cutter for reducing the work to a diameter fitting in said bore; and further, to provide a lathe having such a cutter, a tool for cutting the side of the work, a tool for cutting the end of the work, a tool for severing a finished length of the work, means for feeding the work, and means for operating the feeding means, the cutter and said tools; and further, providing such last-mentioned means which include cams on a driven shaft; and further, to provide improved means for mounting said tools and adjusting the same; and further, to provide in such a lathe means for forming a dowel and the like with a helical groove and a longitudinal groove and beveling the ends of the dowel; and further, to provide in a lathe improved work-feeding means; and further, to provide these parts and means in combinations.

These and any other objects hereinafter appearing are attained by, and the invention finds preferable embodiment in, the lathe and lathe parts particularly described in the body of this specification and illustrated by the accompanying drawings, in which:

Figure 1 is an elevational front view of a lathe;

Figure 2 is an elevational front view (enlarged) of right-hand-end portions thereof, partially sectioned axially on a vertical plane;

Figure 3 is a transverse sectional view of parts thereof taken on line 3—3 of Figure 2;

Figure 4 is a transverse sectional view of such parts taken on line 4—4 of Figure 2 (said parts in these two views being turned a quarter way around from position shown in Figure 2);

Figure 5 is an elevational front view (enlarged) of left hand-end portions of the lathe partially sectioned axially on a vertical plane;

Figure 6 is a transverse sectional view of parts thereof taken on line 6—6 of Figure 5;

Figure 7 is a transverse sectional view of parts thereof taken on line 7—7 of Figure 5;

Figure 8 is a plan view of a ratchet bar of the lathe and adjacent parts thereof, the lathe's frame being sectioned on line 8—8 of Figure 1;

Figure 9 is an elevational front view of the same partially sectioned on line 9—9 of Figure 10;

Figure 10 is a right hand-end view thereof partially sectioned on line 10—10 of Figure 8; 5

Figure 11 is a transverse sectional view of parts thereof taken on line 11—11 of Figure 9;

Figure 12 is an elevational front view of mounting parts of the work piece-severing tool;

Figure 13 is a transverse sectional view thereof, showing its operating cam means, taken on line 13—13 of Figure 12; 10

Figure 14 is a sectional view of parts thereof taken on line 14—14 of Figure 13;

Figures 15 and 16 are side views of said severing tool showing the same in oppositely set positions relatively to the work piece (shown in axial section); 15

Figure 17 is an elevational side view of the mounting parts of the tool for cutting the side of 20 the work piece, partially sectioned on line 17—17 of Figure 18;

Figure 18 is a right hand-end view of the same with said tool, showing the operating cam therefor and partially sectioned on line 18—18 of 25 Figure 17;

Figure 19 is an axial sectional view of parts thereof taken on line 19—19 of Figure 17;

Figure 20 is a right hand-side view of the tool for sizing or reducing the work piece to desired 30 diameter, and mounting parts for said tool;

Figure 21 is a side view of cam means for traveling the ratchet bar and work piece endwise;

Figure 22 is an operative-end view of said 35 means, its shaft being sectioned on line 22—22 of Figure 21;

Figure 23 is a view in perspective of the removable cam member of said means;

Figure 24 is a side view of cam means for operating the tool for cutting the extremity of the work piece; 40

Figure 25 is an operative-end view of said means, its shaft being sectioned on line 25—25 of Figure 24; 45

Figure 26 is a view in perspective of the removable cam member of said means;

Figure 27 is an axially sectional view of cam means for operating the work piece-severing tool, taken on line 27—27 of Figure 28; 50

Figure 28 is a side view thereof, its shaft being sectioned on line 28—28 of Figure 27;

Figure 29 is a view in perspective of the removable cam member of said means;

Figure 30 is a side view of a work piece; 55

Figure 31 is a view of the finished extremity of the work;

Figure 32 is an axial sectional view of said finished work;

5 Figure 33 is an elevational front view of a portion of the lathe showing means for retracting the work piece from the sizing means;

Figure 34 is a plan view of the left hand-end portion of the lathe;

10 Figure 35 is a side view of adjustable means for retracting the tool for cutting the side of the work piece;

Figure 36 is a right hand-side view of means for sizing the work piece;

15 Figure 37 is an axial sectional view thereof taken on line 31—37 of Figure 36 and showing a four-sided work piece therein;

20 Figure 38 is an axial sectional view of a modified construction of parts similar to those shown in Figure 37 but without a sizing tool and showing a rotatable holder sleeve for the work piece hexagonal in cross section;

25 Figure 39 is a transverse sectional view of said holder sleeve and work piece taken on line 39—39 of Figure 38;

Figures 40, 41, 42 and 43 are transverse sectional views of modified constructions of said holder sleeve and work pieces therein;

30 Figures 44 and 45 are respectively side and end views of a plunger or reciprocating rod carrying a tool for cutting the extremity of the work;

Figure 46 is a side view of another example of finished work produced by the lathe as seen in Figures 38, 39 with an end portion of the work 35 piece from which it is severed;

Figure 47 is a plan view of parts of the lathe showing a modified construction thereof whereby helically and longitudinally grooved dowel pins and the like may be made;

40 Figure 48 is an elevational front view thereof partially sectioned axially on a vertical plane;

Figure 49 is an end view of parts of the tail stock thereof (enlarged);

45 Figure 50 is a front view of the same partially sectioned on line 50—50 of Figure 49;

Figure 51 is a plan view of parts shown in Figures 47 and 48;

Figure 52 is a side view of a drill bit which may be inserted into the plunger 100¹;

50 Figure 53 is a side view of a grooved dowel pin; and

Figure 54 is a sectional view of parts shown in Figure 51 taken on line 54—54 of that view; and showing additional adjacent parts.

55 In the embodiment of the invention illustrated by these drawings a lathe is shown having a frame or bed 1 with spaced front and rear sides 2 supported on suitable legs 3 and carrying the operative parts. By this lathe a work piece may be fed

60 or moved lengthwise to cutting tools whereby it is reduced to desired diameter, its side and extremity cut to predetermined form, and finished pieces of work successively severed therefrom.

65 This lathe and its parts and the operation thereof are described as follows. The lathe's head stock parts 4, 5, 6 coaxially spaced along the lathe's frame carry rotatably therein the lathe's mandrel or arbor designated generally 7 comprising the hollow cylindrical outer member 8 and the inner member 9 axially slidably in said outer member and splined therewith by keys 10 in the keyways 11. The open right hand-end of the head stock part 4 is closed by a tubular extension 12 in which the right hand-end portion of the

70 inner member 9 may be moved, this extension 75 having a screw cap 13. The head stock parts 4, 5 are fixed as by bolts 14 on the frame, while the part 6 is movable therealong, its depending edge portions 15 slidably bearing on the upper edges of the frame's sides 2.

5 It will be seen that the mandrel's outer member 8 is rotatably mounted and held against axial movement in the fixed parts 4, 5 of the head stock, while the inner member 9 is thus mounted and held in the slidably movable part 6.

10 A work piece, such for example as is shown at 16 in Figure 30 having conically tapered ends 17, is inserted in the lathe, one of said ends being received in the funnel shaped mouth 18 of the opening 19 extending through the lathe's tail 15 stock 20 fixed on the lathe's frame, said opening 19 axially aligning with the mandrel, and the head stock part 6 is slid along the frame to a position wherein the work piece's other tapered end is received in the socket 21 of the chuck end 20 22 of the mandrel's inner member 9, said member being drawn outwardly by thus sliding the part 6 of the head stock. In such sliding movement the dog 24 of part 6 engages a tooth of the ratchet bar 25 mounted in a groove of a 25 carrying bar 26 slideable or movable parallelly with the mandrel as between pairs of rolls 27 rotatively mounted at 28 on a cross bar 29 extending between the frame's sides 2 as shown in Figure 7. The tail stock 20 fixed on the frame 30 has a preferably removable middle portion 30 (see Figure 37) through which said opening 19 extends, and the funnel shaped mouth 18 of this opening is provided with a cutting tool 31 clamped as by a bolt 32 in a mounting member 33 pivoted 35 at 34 on the right-hand side of the tail stock and adjustable by a set screw 32 relatively to the axis of said opening so that the extreme cutting edge 36 of said tool may be set to register with the circular side 37 of said opening (see Figure 40 20).

To carry out the lathe's operations, the work piece 16 is rapidly rotated and the shaft 46 is simultaneously but slowly rotated by suitable means such for example as are indicated in Figure 1. As shown in this view the mandrel is rotated by an electric motor 38 through the belt 39 on the sheaves 40, 41 of said motor's shaft and the mandrel's outer member 8, and the shaft 46 is rotated in its bearings 47 by the motor 48 through the belt 49 on the sheaves 50, 51 of said motor's shaft and the shaft 42 journalled at 43, and by the belt 52 on the sheaves 53, 54 of shaft 42 and shaft 55 journalled at 56, and by the meshing gears 57, 58 of shafts 55, 46. Thus the work piece 16 is rapidly rotated (the chuck end 22 having means as the threads 59 for turnably engaging the work piece), and said work piece is comparatively slowly fed lengthwise toward the left-hand side of Figures 1 and 5, by the bar 25, 26 engaging the dog 24 of the head stock part 6, said bar being moved to effect such feeding by a cam wheel 60 on said shaft 46 having the cam member 61 detachably mounted thereon as by the screw bolt 62, as particularly shown in Figures 21, 22, 23, this bar 26 having a roll 63 traveling on the cam and surface of said member so that as this roll rides up on the cam's rise 64 between its low and high dwells 65, 66 the work piece is fed and the cutting tool 31 reduces its outer end portion 67 to the desired diameter, as particularly seen in Figure 37, in so doing tapering the work piece's portion 68 (inwardly from its end portion 67) correspondingly with 75

the funnel mouth 18. As this circular end portion 67 is thus fed it is forced into and through the circular opening 19 of the tail stock 20 in which it tightly fits, said end portion having been 5 reduced to such fitting diameter by the proper setting of the cutting tool 31.

Said opening 19 being through the sleeve 69 which is freely rotatable in the tail stock and desirably provided with ball bearings 70 in a 10 race 71 therein, the work piece in its rotation carries said sleeve with it and is firmly held thereby against lateral movement or vibration throughout the various cutting operations to which it is subjected.

15 When the work piece has been thus reduced to the desired diameter and fed lengthwise far enough through opening 19 to provide an end portion 67 projecting from the left hand side of the tail stock far enough for the forming of 20 a finished piece of the desired work (as for example the drawer pull 72 shown in Figures 31, 32), the work piece 16 is held against retracting movement by the high dwell 66 of the cam member 61. Said projecting end portion 67 of the rotating 25 work piece is now cut at its sides by a cutting tool of cross sectional shape corresponding to the desired side formation of the work, such for example as the tool 73. This tool is mounted for adjustment to various positions as particularly 30 shown in Figures 17, 18, 19. As shown in these views, the lever 74 is fulcrumed on a rod 75 on the brackets 76 bolted at 77 on the rear side 2 of the lathe frame to turn on an axis parallel with the mandrel. The short arm 78 of this lever 35 has a cross-sectionally round bearing 79 in which the approximately vertical spindle 80 of a block 81 is adjustable axially and turnably to positions in which it is held by the set screw 82. This block has a spindle 83 approximately parallel with 40 the mandrel, which spindle may be adjustably turned in the bearing 84 of the split member 85 in opposite directions by the set screws 172, 173 threaded in said member and engaging diametrically opposite shoulders 174, 175 of spindle 83, 45 this member 85 being additionally held in such adjusted positions by the set screw 86.

On the upper face 87 of member 85 a slidable block 176 may be clamped by a bolt 88 extending through block 176. On the flat upper face 50 177 of block 176 the cutting tool 73 may be slid and turned to desired adjusted positions and clamped therein by a bolt 178 extending through the clamping bar 89, whereby the adjustment of this tool relatively to the work piece's end portion 67 is effected.

A cam wheel 90 on shaft 46 carries by the bolt 91 a removable cam member 92. It will be seen that as this shaft 46 and cam wheel 90 rotate the roll 93 on the long arm 94 of lever 74 rides up on 55 the cam surface 95 of said member thus swinging the cutting edge 96 of the tool 73 toward and into the side 97 of the end portion 67 of the work piece, along the dotted line *a* which is circularly arcuate relatively to the lever's fulcrum 75. The member 85 may be set by the screws 172, 173 to different angular positions about the axis of the spindle 83 as may be desired to vary the angle at which said cutting edge engages the work piece's side 87, and the tool may be clamped by the bolt 60 178 in desired longitudinal positions for varying its cutting depth, and it may be turned on and parallelly with the face 177 to desired clamped positions. The lever 74 is moved by the cam 92 against the pressure of a spring 179 surrounding the rod 180 threaded at 181 and connected

to a cable or chain 182 passing over a pulley 183 mounted on the frame's rear side 2 and connected at 184 to the member 85, this spring being adjustably tensioned by a nut 185 on the threaded end of said rod, as seen in Figure 35.

5 The cam wheel 90 has an enlarged hub portion 217 fitting in the bore 218 of the cam member 92. A gap 219 in this bore is adapted to receive shaft 46 transaxially whereupon member 92 is slid axially to receive said hub portion fitting- 10 ly in said bore in assembling the parts.

The extremity 98 of the end portion 67 of the work piece may be cut or circularly grooved to desired form, such for example as is shown in Figure 31 which illustrates a finished piece of 15 work—a drawer pull.

This cutting operation is effected by the relative rotary and axially-approaching movements of the work piece and the plunger or reciprocating rod 100 slidable in bearings 101 in the cross 20 bar 102 fastened on the lathe's sides 2 as by bolts 103 and carrying a suitably shaped cutting tool 99 projecting from the inner or right hand-end of this plunger and removably held in adjusted position by a set screw 106 (see Figure 5, 44, 45). 25 This plunger is slid inwardly by the cam wheel 104 on shaft 46 having the cam member 105 removably secured thereto by bolts 106 as shown in Figures 24, 25, 26.

A roll 107 on the downwardly extending arm 30 108 of said plunger travels on the cam end surface 109 of said member. It will be seen that as said shaft and cam member rotate and the roll rides up on the rise 110 of said surface the plunger 100 is slid inwardly to a position in which it is 35 held by the high dwell 111 of said cam surface, during which sliding movement the extremity of the end portion of the work piece is cut.

The finished piece of work (as said drawer pull shown in Figures 31, 32) is now severed from 40 the work piece 16 by a cut-off tool 112. This tool, with its mounting and adjusting means, is particularly well shown in Figures 12-16. As thus shown, said tool is clamped by a set screw 113 in endwise adjusted position in the squared 45 socket 114 of the inner member 115 of an arm 116, slidable in a bearing 117 in the outer member 118 of said arm by a screw 119 threaded at 120 in said outer member and oppositely threaded at 121 in said inner member.

50 The inner member 115 and the tool being thus slid toward the work piece's end portion 67, may be clamped in adjusted position by the set screw 122. This tool-carrying arm 116 is pivotally mounted to turn in a substantially vertical plane, 55 on a bracket member 123 pivoted at 124 on the front side 2 of the lathe frame to be turned in a vertical plane parallel therewith to adjusted positions wherein it is clamped by the screw 125 extending through said member's slot 126 and 60 threaded in said side of the frame. This arm 116 is pivotally mounted on the bracket member 123 by pointed screws 127 threaded in said member's upward arms 128 and engaging in the ends of a threaded rod 129 extending through an opening 65 130 in said arm, on whose opposite sides nuts 131 on said rod are turnably clamped to hold said arm in accurately adjusted positions in the lengthwise direction of said rod and of the lathe's mandrel. The bracket member 123 may be 70 turned on its pivot 124 upwardly to clamped position to incline the tool 112 inwardly to provide a conical depression 132 in the inner end of the severed piece of work as shown in Figure 15, or 75 downwardly to provide said piece with an out-

wardly conical end portion 133 as seen in Figure 16, said bracket member being adjusted to an intermediate position to provide said piece with an end at right angles to its side.

5 This severing tool 112 is operated by means particularly well shown in Figures 13, 27-29. The shaft 46 has a cam wheel 134 on whose side is removably mounted a cam member 135 by a bolt 136. A roll 137 on the downwardly extending portion 138 of the inner member 115 of the arm 116 travels on the cam surface 139 of this cam member.

10 It will be seen that as this shaft 46 and said cam wheel with its member 135 rotate, this roll 15 rides up from the cam surface's low dwell 140 onto its rise 141, the arm 116 is raised so that the tool 112 severs the piece of work from the rest of the work piece 16 in the lathe.

15 It will be seen that this work piece being rotated by the mandrel 7 and moved lengthwise by the rotation of the shaft 46 through its cam elements 60, 61 far enough to cut by the tool 31 a sufficiently long end portion 67 of the work piece to proper diameter for the desired piece 20 of work 72, the rotating work piece is held by the high dwell 66 of cam 60 against axial re-tracting movement while the operations of the other cutting tools are performed; and that these further cutting operations are actuated in 25 the continued turning of shaft 46 by its various cam elements so formed and so angularly spaced about said shaft as to effect these several cutting operations in properly timed sequence.

30 These operations being completed, and the cam elements 60, 61 turning to their low dwell 65, the ratchet bar 25, 26 is drawn by spring 142 to initial position, the work piece's unsevered end portion remaining held in the sleeve 69 and the dog 24 slipping over the teeth of said bar, and 35 the cam elements 104, 105 turning to position wherein the roll 107 of plunger 100 reaches the low dwell 144, the spring 145 draws said plunger back, and the parts are returned to their initial positions, the lathe's cycle of operations being 40 completed and its parts ready for the next cycle for forming another piece of work from the end of the work piece.

45 In order to withdraw the stub of the exhausted work piece from the sleeve 69, I provide a hand lever 146 fulcrumed at 147 on the front side of the lathe, its arm 148 engaging the pivot pin 149 of the dog as shown in Figure 33.

50 In Figures 38-43 various forms 69¹, 69², 69³, 69⁴ and 69⁵ are shown which (and others not 55 shown) may be adopted in place of the sleeves 69 in the tail stock 20. In these views, the work piece 16¹, 16², 16³, 16⁴ and 16⁵ are not shown as being reduced by such a cutter tool as is shown 60 at 31 in other views to form a cross sectionally round end portion 67, but the cross-sectionally 65 rectangular, polygonal or fluted work pieces pass through the tail piece 20 in their initial form, and the projecting end portions thereof are shaped and severed in the manner shown in other views.

65 The sleeves 69, etc. in which the work pieces tightly fit as shown in Figures 37-43 have a radial flange 150 at their inner ends against which abuts one member 151 of the ball race 71, 70 the members 151, 152 of this race being removably held in the circular socket 153 in the middle portion 30 of the tail stock 20 by a ring plate 154 threaded at 155 on said sleeve, and all these 75 parts being removably held in said socket by screws 156 extending through the ring plate 157

and threaded in the middle portion 30 of the tail stock.

5 In Figures 8, 9 and 10 is shown means for cushioning the retracting movement of the bars 25, 26 and for insuring the engagement of the dog 24 with the teeth thereof, said means including a spring or resilient rubber 158 which the inner end of the retracting bar strikes, held in a socket 159 of a member 160 adjustable longitudinally of the lathe by a bolt 161 extending through its slot 162 and threaded in the bracket 163 mounted at 164 on the frame. This spring or rubber may be moved in said socket to the desired degree by a screw 165 threaded in said member and engaging the spring's inner end. The carrying bar 26 has a rearward side extension 166 with an inclined face 167 on which slidably bears in said bar's movement a leaf spring 168 mounted by a bolt 169 on said bracket, its tension being adjusted by the set screw 170.

20 In Figure 46 is shown in side view, another example 72¹ of finished work that may be made by this lathe, such example being the handle of a screw driver or the like. This piece's end portions 191, 192 are properly shaped by tools spaced 25 apart to leave the middle portion 190 of the piece uncut, said tools being mounted and operated in the same manner as the side-cutting tool 73 shown in other views. This piece 72¹ being severed as in other cases from the rest of the work 30 piece 16¹, other like pieces may be successively formed and severed therefrom.

25 It will be seen that the various cam members may be replaced with others having desired cam surfaces; that the cam wheels carrying said 35 members may be secured by their shown set screws in turned positions on the shaft 46 to provide desired sequence of operation of the cutting tools; that ratchet bars 25 having teeth spaced at desired intervals may be clamped by the bolt 40 171 in the carrying bar 26; and that the various cutting tools may be adjusted with great nicety to desired operative positions, etc. It will also be seen that the cutting tools are so mounted that their cutting edges extend toward the front of the 45 lathe, i. e., toward the operator, so that the chips are thrown away from him.

50 In Figures 47-51 and 54 is shown a modified construction of portions of the lathe whereby helically and longitudinally grooved dowel pins 50 and the like may be made and their ends tapered. As thus illustrated, the plunger 100¹ has a bore 193 in its inner end in which may be inserted the shank of an extension member 194 clamped by a set screw 195. This member has an axial- 55 offset portion 196 with a squared socket 197 in which the tool 198 is clamped in adjusted position by the set screw 199. The end portion 67¹ of a rotating work piece 16¹ formed and held projecting from the tail stock 20 (as hereinbefore 60 described) is grooved longitudinally at 214 by tools 210 adjustably secured by set screws 211 in radial bearings 212 formed in the side of the sleeve 69⁶ which rotates with the work piece, this longitudinal grooving being done during the 65 feeding of the work piece as hereinbefore described.

70 The rotation of the work piece is very rapid and so is its feeding movement; but the movement of the plunger 100¹ toward the right hand- 70 side of Figures 47 and 48 is about twice as fast as the feeding movement of the work piece in the opposite direction, effected by the sharp rise 208 of the cam member 105¹ on shaft 46 on which cam rides the roll 107 on arm 108 of plunger 100¹. 75

As a length 67¹ of the work piece sufficient to form the dowel (say a length of two inches) is fed far enough the approaching tool 198 engages it and, as the movement of plunger 100¹ carrying this tool and the opposite feeding movement of the work piece continue, said tool cuts the helical groove 202, the relative speed of movement of this tool and the fed movement of the work piece being such that said tool begins to cut the helical groove at the time the work piece has been fed to a position about half said dowel length (i. e. about one inch) from the left hand-side of the tail stock 20. The helical groove having been thus cut the entire length of the dowel, the plunger 100¹ and tool 198 stop movement, the roll 107 now riding on the high dwell 207 on the cam member 105¹. During this stopped movement and as shown in Figure 54, a tool 215 is moved toward the rotating work piece to form a circular groove 203 therein. Said tool 215 is thus moved by suitable means as by being mounted by the bolt 88 on the block 85 in place of the tool 73 shown in Figure 18. This circular groove being formed, the cutoff tool 112 mounted as hereinbefore described on the arm 115 as shown in Figure 13 moves upwardly into said circular groove to sever said dowel from the work piece. This circular groove provides bevelled or tapered opposite ends 201 of the dowel 72² as shown in Figure 53. These operations being finished, the roll 107 rides down on the sharp drop 216 of said cam member whereupon the spring 145 suddenly retracts tool 198 to initial position preparatory to forming the next dowel.

35 In Figure 52 is shown a drill or augur bit 213 which may be inserted in the plunger's bore 193 to form an axial hole in the work piece.

The invention being intended to be pointed out in the claims, is not to be limited to or by details 40 of construction of any particular embodiment thereof illustrated by the drawings or hereinbefore described.

I claim:

1. In a lathe: a tail stock; a member mounted 45 in the stock for freely rotative movement with the work about the axis of the lathe's turning operation, said member having a circular bore therethrough coaxial with said axis receiving and holding the work therein against transaxial movement but permitting the free axial feeding movement of the work through the bore.

2. In a lathe: a tail stock having a cutter for 50 reducing the cross-sectional area of the work fed

thereto; a member mounted in the stock for freely rotative movement with the work about the axis of the lathe's turning operation, said member having a circular bore therethrough coaxial with said axis receiving and holding the 5 work against transaxial movement but permitting the free axial feeding movement of the work through the bore.

3. In a lathe: a cutting tool; a tail stock; a member mounted in the stock for freely rotative 10 movement with the work about the axis of the lathe's turning operation, said member having a bore therethrough coaxial with said axis receiving and holding the work against transaxial movement but permitting the free axial feeding 15 movement of the work through the bore; means for simultaneously feeding and rotating the work whereby a longitudinal groove in the work is cut by the tool, said tool being rotatable with the work. 20

4. In a lathe: a frame; a lathe stock movable on the frame in the work's axial direction; work-feeding means comprising a bar movable in said direction on the frame and having an inclined side portion and spaced teeth; a dog on said stock 25 engaging the teeth; a spring pressing said inclined side portion to move the bar into engaging position with the dog.

5. In a lathe: a block turnably mounted on the 30 lathe's frame and having arms spaced in the frame's longitudinal direction; means for releasably fastening the block in turned position; a threaded rod; a tool-carrying member movable along the rod; nuts on the rod at the opposite sides of said member for clamping the same in 35 adjusted position on the rod; aligned screws threaded in said arms and having at their inner ends bearings on which the rod is turnable, said screws being turnable in said arms to move and hold the rod in lengthwise adjusted position. 40

6. In a lathe: a lever fulcrumed on the lathe's frame to be swung in a vertical plane and having an axially vertical bearing; a block turnable in said bearing to adjustably held positions; a second block mounted on the first-mentioned block 45 to turn in a vertical plane to adjustably held positions; a tool-carrying member adjustably mounted on the second-mentioned block; a tool adjustably mounted on said member; means operated by the lathe's driving means for swinging 50 the lever to move the tool toward the work in the lathe.

CHARLES W. SMITH.
